UNITED STATES PATENT OFFICE.

JOHN WILLIAM PRITCHETT, OF LONDON, ENGLAND.

FASTENING FOR GLOVES, BOOTS, &c.

SPECIFICATION forming part of Letters Patent No. 269,706, dated December 26, 1882.

Application filed June 21, 1882. (No model.) Patented in England March 29, 1882, No. 1,531.

To all whom it may concern:

Be it known that I, JOHN WILLIAM PRITCHETT, of London, England, have invented a new and useful Improvement in Fasteners for 5 Gloves, Boots or Shoes, Stays, and other Articles of Wearing-Apparel, (for which I have obtained a patent in Great Britain, bearing date the 29th day of March, A. D. 1882, No. 1,531,) of which the following is a full, clear, and ext 10 act description, reference being had to the annexed drawings, in which—

Figure 1 is a perspective view of my improved fastener. Fig. 2 is a longitudinal section taken 15 centrally through the same. Fig. 3 is a top or plan view with the tongue engaged by the spring-catch. Fig. 4 is a spring-catch, with a modified construction of catch.

My invention relates to that class of fasteners in which a tongue or lever is pivoted to a 20 plate and the latter secured to the article to be fastened at one side of the opening therein, so that by passing the hinged tongue through an eye in the article at the opposite side of the said opening the edges of the article can be 25 drawn together and the tongue then locked down upon the plate.

The object of my improvement is to provide a simple, convenient, and efficient fastening device for a variety of articles of wear, and es 30 pecially for securing gloves at the wrist.

To such end my invention consists in a fastener comprising a bed-plate provided with a hinged tongue, and a spring-catch consisting of a slide-bar having a catch for engaging the 35 free end of the tongue, and a spring located within a recess in the bed-plate and adapted to cause the catch to automatically engage the tongue, all of which will be more fully herein-after explained:

In the drawings, A indicates the metal bed-plate, which can be of rectangular, oval, or other shape, as may be desired. This bed-plate is provided with a spring-catch consisting of a 40 sliding bar or catch proper, B, arranged to slide in a suitable guideway or recess in the bed-plate, and having its inner or shank end surrounded by a spring, C, which is located in said recess, and arranged to press at one end against a shoulder on the sliding latch, so as 45 to throw the latch forward.

The recess or guideway in which the spring

and the rear end of the catch are inclosed can be conveniently formed by making a depression, a, in the plate and then applying a cap-plate, D, over said depression. The forward 55 end of the catch, which projects from the bed-plate, is provided with a curved finger, b, extending laterally from the top or outer side of the catch, said finger being formed by bending back the outer end of the catch and then 60 bending a portion of said end at right angles to the catch; or said finger can be made separately and secured to the catch. The catch or tongue E is hinged at one end to the bed-plate, at one end of the latter, and is formed so that 65 when swung down upon the bed-plate its free end, which is provided with an opening, e, shall be engaged by the finger b of the catch.

The bed-plate is provided with tangs F for fastening it to the article requiring a fastener; 70 or said bed-plate can be provided with perforations and sewed to the article by passing the threads through said perforations.

In the drawings, G' G' respectively indicate the meeting edges to be drawn together and 75 secured by my improved fastener, one of said parts being provided with an eye, H, through which the tongue is passed, so as to make the operator to draw the edges together. After the tongue has been passed through said eye it 80 can be swung down toward the bed-plate, so that when one edge of the opening in the tongue strikes the finger b on the spring-latch the latter will be pressed back until said finger is in position to enter the opening on the tongue, 85 after which the catch will spring forward as soon as the tongue is well down, thereby automatically locking the tongue.

To unlock the tongue it will only be necessary to push back the latch and raise the tongue, 90 so that the latter can be slipped out of the eye in the glove or other article.

In Fig. 4 the catch is provided at its outer end with a ring or eye, I, having a beveled edge, i, against which the end of the tongue will strike 95 when the said tongue is swung down, and thereby throw the catch out, so as to allow the end of the tongue to pass through the ring I. In this case the spring is a retractile spring, whereby, after the free end of the tongue has entered 100 ring I, the spring will draw the catch back, and thereby lock the tongue. As shown in the

drawings, the tongue has a bend, e' , so as to allow space between the tongue and the top of the bed-plate for the edge of the article through which the tongue passes.

5 If preferred, a plate, K, can be applied to the article of wear on the side opposite to that on which the fastener is located, and the tangs passed through openings in said plate and then clamped thereon.

10 Having thus described my invention, what I claim is—

A fastener for articles of wear, comprising a bed-plate provided with a hinged tongue and a spring-catch consisting of a slide-bar having 15 a catch for engaging the free end of the tongue,

and a spring located within a recess in the bed-plate and adapted to cause the catch to automatically engage the tongue, said bed-plate being applied near one edge of the article to be fastened, and the tongue being adapted to pass 20 through an eye located near the opposite edge of the article, substantially as described.

In witness whereof I have hereunto signed my name in the presence of two subscribing witnesses.

JOHN WILLIAM PRITCHETT.
